Primary Examiner — Catherine S Posthauer*Assistant Examiner* — Riah D Buchanan(74) *Attorney, Agent, or Firm* — Nixon Peabody LLP(57) **CLAIM**

The ornamental design for a child-resistant container, as shown and described.

DESCRIPTION

FIG. 1 is a front perspective view of a child-resistant container, showing our new design.

FIG. 2 is a back perspective view thereof.

FIG. 3 is a front elevation view thereof.

FIG. 4 is a back elevation view thereof.

FIG. 5 is a side elevation view thereof, the opposing side being identical thereof.

FIG. 6 is a bottom plan view thereof; and,

FIG. 7 is a top plan view thereof.

The broken lines are shown for the purpose of illustrating parts of the article that form no part of the claim.

1 Claim, 4 Drawing Sheets---
